(57) CLAIM

The ornamental design for a blouse, as shown and described.

DESCRIPTION

FIG. 1 is a front perspective view of a blouse showing my new design in use;

FIG. 2 is a rear perspective view thereof;

FIG. 3 is another front perspective view thereof;

FIG. 4 is a left side perspective view thereof, showing the sleeves of the blouse in a raised position;

FIG. 5 is a right side view thereof;

FIG. 6 is another front perspective view of FIG. 1;

FIG. 7 is a top plan view of the blouse not shown in use; and, FIG. 8 is a bottom plan view thereof.

The broken lines shown in FIGS. 1-3 and 6, showing portions of the human form and a portion of a skirt, are included for illustrative purposes to show the design in use and form no part of the claim.
